SIDE FRAME FOR CAR TRUCKS

Filed March 18, 1926

Patented July 2, 1929.

1,719,525

UNITED STATES PATENT OFFICE.

HOWARD D. TAYLOR, OF NEW YORK, N. Y., ASSIGNOR TO FLEXIBLE TRUCK CORPORATION, OF PHILADELPHIA, PENNSYLVANIA, A CORPORATION OF DELAWARE.

SIDE FRAME FOR CAR TRUCKS.

Application filed March 18, 1926. Serial No. 95,529.

The invention relates to cast metal side frames for car trucks and seeks to provide an improved side frame in which the metal is economically distributed to afford a strong construction and particularly at the ends of a cast steel side frame having integral journal boxes. A further object of the invention is to provide a stout construction at the central portion of the side frame and which is particularly adapted for use with side frames of the type set forth in an application for Letters Patent filed in the United States Patent Office May 16, 1924, Serial No. 713,675, Patent No. 1,594,576, dated August 3, 1926, and which is provided with an enlarged central bearing opening for receiving a relatively oscillating bolster carrier.

The invention consists in the features of improvement hereinafter set forth, illustrated in preferred forms in the accompanying drawing, and more particularly pointed out in the appended claims.

In the drawing:

Fig. 1 is a view partially in side elevation and partially in longitudinal section, of the improved side frame.

Figs. 2 and 3 are transverse sections on the lines 2—2 and 3—3 respectively of Fig. 1.

Fig. 4 is an inverted plan view of one end of the side frame.

Figs. 5 and 6 are cross sections of the compression and tension members of the side frame, taken on lines 5—5 and 6—6 respectively of Fig. 1.

Fig. 7 is a longitudinal half section of a modified form of the side frame, and

Fig. 8 is a detail section on the line 8—8 of Fig. 7.

The improved side frame comprises upper and lower or compression and tension members 10 and 11, journal boxes 12, and connecting struts or columns 13, all formed integrally of cast steel. The compression and tension members are preferably reversely arched and their central portions are arc-shaped in the preferred form shown, and merge into oppositely inclined, substantially straight portions. The upper or compression member comprises side walls or flanges 14 and a transverse web 15 which is substantially continuous throughout the length of the compression member and preferably extends along its upper edge so that this member is of inverted U-shape in section throughout the greater portions of its length. Intermediate

their center and end portions the lower edges of the side flanges 14 are preferably thickened to provide stiffening beads 16. The ends of the compression member extend over the journal boxes and its transverse web and side flanges merge into the top walls 17 of the journal boxes with the extreme downturned end portions of the web merging into the outer edges of the journal box tops.

The tension member 11 comprises side walls 18, in the planes of the side walls 14 of the compression member, and transverse webs 19 and 20 extending along its upper and lower edges. One of the transverse webs of the tension member is continuous from end to end of the side frame and the other is preferably provided with elongated openings between its central and end portions, so that the tension member has central and end portions of closed box section and intermediate portions of U-section. In the forms shown in Figs. 1 to 6, the upper transverse web 19 of the tension member is continuous and its lower web is provided with elongated openings 21. In the form shown in Figs. 7 and 8, the lower web is continuous and elongated openings 22 are formed in the intermediate portions of the upper transverse web. Preferably, as shown, the edges of the openings 21 and 22 in both forms are provided with stiffening beads 23 and 24 respectively.

The ends of the tension member are disposed immediately below the end portions of the compression member and merge into the upper portions of the inner side walls of the journal boxes, with the ends of its transverse web 19, which are slightly curved as shown, in line with and merging into the inner edges of the top walls 17 of the journal boxes. The ends of the transverse web 19 and the top walls of the journal boxes form lower walls for the end portions of the compression member so that such end portions are of closed box section and, as most clearly shown in Fig. 2, the end portions of the side frame adjacent the journal boxes are of double box section. In this way, stout end constructions are provided in a side frame having integral journal boxes and it is not necessary to provide vertical stiffening fins between the compression and tension members and the journal boxes. Also, the arrangement of the box sections of the compression and tension members merging respectively

into the top and the upper portions of the side walls of the journal boxes, is such as to readily withstand the stresses to which these portions of the side frame are subjected in service. Preferably, as shown, the extreme end portions of the lower transverse web of the tension member are downwardly curved and triangular stiffening gussets 25 (see Figs. 1 and 4) in alignment with such end portions, 10 extend between the ends of the tension member and the side walls of the journal boxes to resist transverse strains.

The central portion of the tension member is, as stated, of closed box section and extends below the central opening of the side frame that receives the transverse connecting means of the car truck, and the central portion of the upper transverse web 19 of the tension member forms part of a transverse web 26 that extends about the central opening and between the side flanges 14 and 18 of the compression and tension members. This web 26 forms the inner walls of the struts or columns 13 and the lower wall of 23 the central portion of the compression member so that the part of the compression member above the central opening is of closed box section. Preferably also, the struts or columns 13 at the sides of the central opening 30 are of hollow box section having side walls in the planes and forming continuations of the side flanges 14 and 18, and also having transverse webs 27 extending between the lower edges of the compression member and 35 the upper edges of the tension member.

In the construction shown, the transverse web 26 about the central opening of the side frame is cylindrical, projects slightly beyond the side walls or flanges of the compression 40 and tension members to provide projecting circular flanges 28 and forms a bearing opening for a relatively oscillating bolster carrier. In the form shown, as in the construction set forth in the prior application referred 45 to, the bolster carrier ring 29 is formed of cast metal, is provided at its lower portion with a horizontal supporting sill 30 for one end of a spring plank 31, and with integral guides 32 at its sides for cooperating with the 50 end portion of a truck bolster 33, the latter being held in position and in interlocked relation with the bolster guides 32 by springs 34 arranged in the carrier ring between the ends of the spring plank and bolster. Also, 55 as set forth in the prior application, the carrier ring is held in position in the side frame by keys 35 secured within pockets in the side portions of the central opening of the side frame and engaging elongated slots in the 60 bolster carrier ring, thus interconnecting these parts in a manner permitting the relative oscillating movement thereof as the car truck passes over irregularities in the track.

In the improved construction shown, the 65 pockets for the keys 35 are formed by webs

36 extending between the webs 26 and 27 and connected to the side walls of the struts by stiffening webs 37 (see Figs. 1 and 3). The side walls and the webs 36 are provided with openings for receiving bolts or the like by 70 which the keys 35 are secured in position.

The improved side frame has a central portion of stout construction which permits of the formation of a very large central opening that is particularly well adapted for 75 accommodating a relatively oscillating bolster support and the springs and bolster carried thereby. Preferably, as shown, the hollow portions of the improved side frame are provided with core openings 38. Preferably 80 also, brake hanger supports 39 are cast integral with the side frame. Changes may be made in the details set forth without departure from the scope of the invention as defined in the appended claims. 85

I claim as my invention:

1. A cast metal side frame for car trucks having integral journal boxes and compression and tension members, said compression member merging into the top walls of the 90 journal boxes and said tension member merging into the upper portions of the inner side walls of the journal boxes and each of said members having closed box sections adjacent the journal boxes, substantially as described. 95

2. A cast metal side frame for car trucks having integral journal boxes and compression and tension members merging into the journal box tops and inner side walls respectively, each of said members having a transverse web and vertical side flanges and closed box sections adjacent the journal boxes, substantially as described. 100

3. A cast metal side frame for car trucks having integral journal boxes and compression and tension members merging respectively into the journal box tops and the upper portions of the inner side walls of the journal boxes, said members having transverse webs and inner and outer vertical side walls 111 forming superposed, closed box sections adjacent the journal boxes, substantially as described.

4. A cast metal side frame for car trucks having a central opening for receiving the 115 transverse connecting means of the truck, and comprising compression and tension members, and integral columns and journal boxes, said members having box sections above and below said central opening, and double box 120 sections adjacent the journal boxes, substantially as described.

5. A cast metal side frame for car trucks having a central opening for receiving the transverse connecting means of the truck, and 125 comprising reversely arched compression and tension members, and integral columns and journal boxes, said members having hollow box sections adjacent the journal boxes and above and below the central opening and in- 130

- verted U-sections between the central and end portions thereof.
6. An integral cast metal side frame for car trucks having a central bearing opening for receiving a relatively oscillating carrier having a spring seat and bolster guides in the plane of the side frame, and having compression and tension members of hollow continuous wall section above and below said opening. 45
7. An integral cast metal side frame for car trucks having a central bearing opening for a relatively oscillating carrier having a spring seat and bolster guides in the plane of the side frame, comprising inner and outer side walls and upper and lower walls forming, with the adjacent portion of the side walls, upper compression and lower tension members, said tension member being of hollow box section below said opening. 55
8. A cast metal side frame for car trucks having an enlarged central portion provided with a cylindrical bearing opening for a relatively oscillating carrier having a spring seat and bolster guides in the plane of the side frame, and comprising reversely arched compression and tension members integrally connected at their ends and having transverse webs and side flanges and central portions of box section forming the upper and lower portions of the bearing opening and columns extending between and integral with said members forming the side portions of such opening. 60
9. A cast metal side frame for car trucks having an enlarged central portion forming a bearing opening for receiving and supporting a relatively oscillating bolster carrier and comprising compression and tension members and integral journal boxes and columns, the latter and the central portions of said compression and tension members forming the cylindrical bearing opening, said members and struts comprising transverse webs and vertical side flanges, and said members having box sections above and below said cylindrical bearing opening and U-sections between the central and end portions thereof, substantially as described. 65
10. An integral cast metal side frame for car trucks having an enlarged central portion forming a bearing opening for receiving and supporting a relatively oscillating bolster carrier and comprising compression, tension and strut members formed of inner and outer side walls and transverse webs disposed between the edges of said side walls and extending continuously throughout the lengths of the compression and tension members and continuously about said bearing opening and providing the latter with a cylindrical bearing portion and the compression and tension members with hollow box sections of contracted height above and below the central bearing opening. 70
11. A cast metal side frame for car trucks having an enlarged central portion provided with a cylindrical bearing opening for a relatively oscillating bolster carrier and comprising compression and tension members and integral journal boxes and struts, the latter and the central portions of said compression and tension members forming the cylindrical bearing opening, said members and struts comprising transverse webs and vertical side flanges, and said members having box sections above and below said cylindrical bearing opening and U-sections between the central and end portions thereof, substantially as described. 75
